(57) **CLAIM**

I claim the ornamental design for a jug-shaped loudspeaker, as shown and described.

DESCRIPTION

FIG. 1 is a perspective view of the loudspeaker showing my new design;

FIG. 2 is a front view of the loudspeaker;

FIG. 3 is a left side view of the loudspeaker;

FIG. 4 is a right side view of the loudspeaker;

FIG. 5 is a rear view of the loudspeaker;

FIG. 6 is a top plan view of the loudspeaker;

FIG. 7 is a bottom plan view of the loudspeaker; and,

FIG. 8 is an exploded view with tweeter and wire adapter disconnected.

The broken line showing the details of the top mesh configuration of FIGS. 1, 2, 4, 6 and 8 and the details of connection of the top part with the bottom part of the jug in FIG. 8 is for illustrative purposes only and forms no part of the claimed design.
